PHOTOELECTRIC CELL

Anthony H. Lamb, Hillside, N. J., assignor to
 Weston Electrical Instrument Corporation,
 Newark, N. J., a corporation of New Jersey

Application August 26, 1944, Serial No. 551,416

5 Claims. (Cl. 136—89)

1

This invention relates to photoelectric cells of the barrier layer type and particularly to the construction or arrangement of the current collector system associated with the translucent upper electrode of the cells.

Photocells as manufactured commercially in various shapes have usually comprised a back electrode of desired shape carrying a layer of light-sensitive material such as copper oxide or crystalline selenium, a translucent electrode layer upon the light-sensitive material, and a current collector rib of cadmium or other soft metal upon and extending around the periphery of the translucent electrode. The terminal connections to the photocells have usually taken the form of spring fingers bearing upon the back electrode and the current collector rib with substantial pressure.

The current collector or pick-up rib prevents a short-circuiting of the cell through a crushing of the translucent electrode layer by the spring terminal fingers, but the relatively thick and opaque pick-up rib decreases the current output by blocking light from a substantial portion of the light-sensitive layer and increases the "dark leakage" of the photocell. The term "dark leakage" is applied to the effect of the portion of the light-sensitive layer that is not exposed to light and which forms a current-conducting path in parallel with the external photocell circuit. The light-sensitive layer is of high resistance but that portion which is not exposed to light forms an internal path through which a part of the generated current circulates, thereby diminishing the current in the external or useful circuit. Furthermore, the formation of the current pick-up rib by a metal-spraying process results in "root leakage" that may be substantial or, in some instances, may short-circuit the cell. The sprayed metal of the rib penetrates to some extent into the crystalline light-sensitive layer to form "roots" that approach the back electrode to a greater or less extent, thereby reducing the resistance of the "dark area" of the light-sensitive layer to a value substantially less than that which would obtain if the current collector rib could be separately formed and pressed upon the translucent electrode layer.

Objects of the present invention are to provide photocells that have a substantially increased current output for a photocell of any given size. An object is to provide photocells with current collector systems that increase the useful light-sensitive areas of the photocells and that reduce dark leakage and root leakage. An object is to

2

provide a photocell having a current collector of small area located substantially centrally of the translucent electrode layer. More specifically, an object is to provide a photocell having a central or approximately central aperture surrounded by a current collector ring of small size, and a terminal connection welded or soldered to the current collector ring.

These and other objects and advantages of the invention will be apparent from the following specification when taken with the accompanying drawing in which:

Fig. 1 is a central section through a photoelectric cell embodying the invention; and

Fig. 2 is an elevation of the same.

In the drawing, the reference numeral 1 identifies a circular disk electrode of iron or a ferrous alloy that has a small central aperture. A layer 2 of material, for example selenium, is deposited upon and converted in known manner into the crystalline light-sensitive state, and a translucent outer electrode layer 3 is deposited or formed upon the layer 2. The particular process steps for forming the multiple layer photoelectric cell as so far described are not essential features of the invention and any known or desired processes may be employed.

In accordance with this invention, a small diameter and small area ring 4 of cadmium or a soft metal is deposited around the central aperture of the cell assembly by a metal spraying process. A spring terminal connection may be made to the collector ring but it is convenient, and usually preferable, to form a permanent metallic connection. As illustrated, the strands 5 of a flexible insulated terminal conductor 6 that extends through the central aperture are separated and bent outwardly to overlie the ring 4 to which they are mechanically and electrically connected by weld metal or solder 7. The other end of the terminal conductor 6 may be provided with a lug or contact 8 for connecting the cell into an external circuit. One end of an insulated wire 9 is secured to the back electrode 1 by solder or weld metal 10, and a lug or contact 11 is soldered or clamped upon the other end of the insulated wire 9.

The small area of the collector ring 4, as compared with the conventional collector ring elements at the periphery of the outer electrode layer, results in an increased current output due to the increased active area of the translucent electrode layer 3 and to the reductions in dark leakage and root leakage currents. It is to be noted that the length of the path of current flow

from any remote part of the electrode layer to the central collector ring **4** is substantially the same as in the prior construction that included a peripherally arranged collector ring. The advantages of a small current collector area are thus obtained without introducing any conditions that offset the advantages.

It is to be understood that the invention is not limited to the construction herein illustrated and described as various changes may be made in the size, shape and arrangement of the cell components and terminal connections without departing from the spirit of my invention as set forth in the following claims.

I claim:

1. A photoelectric cell of the current-generating type including a back electrode, a layer of light-sensitive material on the back electrode, a translucent electrode on the light-sensitive layer, and a current collector rib of soft metal deposited upon a part of the translucent electrode; characterized by the fact that said current collector rib is limited to a small area located substantially centrally of the translucent electrode.

2. A photoelectric cell of the current generating type comprising a back electrode having an

opening therethrough, a layer of light-sensitive material on said back electrode, a translucent electrode on said light-sensitive layer, and an annular current collecting rib deposited upon said translucent electrode at the periphery of said opening.

3. A photoelectric cell as recited in claim 2, in combination with a terminal conductor extending through said opening and soldered to said collector rib.

4. A photoelectric cell of the current-generating type comprising a layer of selenium between a back electrode and an outer translucent electrode, said back electrode being a circular disk with a central aperture, a current-collecting ring deposited upon said outer electrode at the periphery of said central aperture, and a terminal connection extending through said aperture and soldered to said collecting ring.

5. A photoelectric cell as recited in claim 4, wherein said connection comprises a multi-strand insulated conductor, the ends of the several strands being separated from each other and soldered to said current collector ring.
